HAIR CURLING DEVICE

Henry Clay Whittaker, Memphis, Tenn.

Application May 10, 1946, Serial No. 668,882

2 Claims. (Cl. 132—9)

1

This invention relates to combs and is more particularly directed to improvements in rat-tail combs.

An object of the invention is the provision of a device which may be readily applied to the rat-tail of a comb for clamping the free end of a strand of hair in such a position on a sheath embracing the rat-tail that when said strand is coiled around the sheath, the coiled strand may be slipped off said sheath between the arms of a bobby pin which is carried by the outer free end of the sheath, said end of the sheath being so constructed that it will spread the arms of the pin for more conveniently receiving the curled strand.

Another object of the invention is the provision of a device for aiding in curling a strand of hair and for spreading the arms of a bobby pin so that the curled strand may be easily moved between said arms and clamped therebetween when said pin and strand are slipped off the end of a sheath which is removably mounted on the rat-tail of a comb.

A further object of the invention is the provision of a device having a sheath which may be readily applied to the handle of a rat-tail comb for clamping the free end of a strand of hair to the sheath so that said strand may be curled around said sheath, an end of the sheath extending beyond the free end of the handle of the comb and equipped with means thereon for holding and spreading the arms of a bobby pin in such a manner that the curled strand may be shifted along the sheath into and between the spread arms of the pin, said pin being readily releasable from the sheath so that the arms of said pin will contact and grip the curled strand therebetween.

The invention consists in the novel construction, arrangement and combinations of parts hereinafter more particularly described and claimed.

In the drawings:

Figure 1 is a longitudinal side view in elevation of a rat-tail comb showing a hair curling device applied thereto.

Figure 2 is a fragmentary side view of the comb showing a strand of hair in coiled formation on a sheath of the curling device adjacent the spreading arms of a bobby pin.

Figure 3 is a longitudinal vertical section of the curling device taken along the line 3—3 of Figure 4, and

Figure 4 is a transverse vertical section taken along the line 4—4 of Figure 3.

2

Referring more particularly to the drawings, 10 designates a comb having a rat-tail or handle 11. The free end of the handle has a portion cut off so that the handle 11 is slightly shorter than the normal handle employed in rat-tail combs for a purpose which will be presently explained.

A metal sheath 12 which may be formed of aluminum, stainless steel or other suitable material, is tapered from a sheared-off inner end 13 10 to an outer reduced end 14, so that said sheath will receive neatly the similarly tapered handle 11 of the comb. The inner end of the shield at the bottom thereof is slightly spaced from the bottom edge of the handle as shown at 15 (Figure 4).

15 The outer end 14 of the sheath has an opening 16 of sufficient diameter to receive one arm 17 of a bobby pin 18. The other arm 19 of said pin is in engagement with an annular shoulder 20 on the end 14 of the sheath, so that when the arm 17 is forced into the opening 16, the other arm 20 will be spread outwardly, as shown in Figures 1 to 3, inclusive.

25 A clamp or bar 25 is curved transversely to fit neatly the bottom portion of the shield 12, and is tapered from the inner end 26 of the outer free end 27 to conform to the tapering of the shield 12. An operating member or loop 28 extends downwardly from the inner end of the clamp. This loop is an extension of the metal clamp and 30 is formed from a flat strip of spring metal which extends downwardly in integral formation from the inner end of the metal bar 25. The flat strip is bent upwardly as shown at 30 with the free end 31 bent inwardly and inserted into the space 15 35 between the lower surface of the inner end of the handle and the adjacent inner surface of the sheath 12, as shown in Figures 3 and 4. The inserted end 31 of the operating member 28 is retained frictionally in place by the handle 11. 40 Since the member 28 is made of resilient materials, pressure on said member towards the left in Figure 1 will oscillate the clamp to the dotted line position.

The operation of my device is as follows: 45 When it is desired to curl a strand 35 of hair, pressure is exerted on the member 28 so that the clamp 25 will assume the dotted line position shown in Figure 1. The end of the strand is placed between the clamp and the shield 12 and the member is released so that the strand will be held securely between the shield and clamp. The comb is then rotated to curl the strand around said shield as shown in Figure 2.

One leg 17 of the bobby pin is then forced 50 through the opening 16 at the outer end of the

sheath until the other leg engaging the annular shoulder 20 embracing said opening is spread sufficiently apart from the leg 17 for receiving the strand of hair.

In order to move the curled strand of hair from the shield 12 it is necessary to press sufficiently upon the members 28 to relieve the clamping action of the member 25 whence the curled strand is shifted towards the end of the sheath until it rests below the arm 19 of the pin 18. The curled strand and the pin are simultaneously removed from the sheath, whereby the arm 19 of the pin 18 will clamp the strand on the arm 17 of said pin.

The rat-tail 11 may be withdrawn from the sheath 12 after the strand 35 has been curled on said sheath, thereby releasing the gripping action of the clamp 25 so that the curled strand of hair may be shifted along said sheath below the arm 19 of the pin 18. The removal of the pin from its position on the end of the sheath will return the arm 19 of the pin towards the arm 17 for clamping the strand between said arms.

The end of the rat-tail 11 is cut off at 40, so that the arm 17 of the bobby pin may be moved to the position shown in Figure 3, to spread the arm 19 of said pin sufficiently away from the outer end of the shield 12 for the reception of the strand of hair 35.

The tapered handle or rat-tail of the comb 10 acts not only as a convenient support for the sheath 12 of the combined hair curler and spreading means for the arms 17 and 19 of the bobby pin 18, but frictionally retains the clamping member 25 in position in the sheath.

The sheared beveled inner end 13 of the sheath 12 provides sufficient space between the lower inner edge of the sheath 12 and the inner end 36 of the comb 10 to permit rocking of the member 28 of the clamp 25 for moving said clamp away from said sheath (Figure 1).

Although a preferred and practical embodiment of the invention is disclosed herein, it is to be understood that various modifications may be made within the scope of the appended claims.

I claim:

1. A hair curling device comprising a sheath tapered to fit a tapered handle of a comb, the

outer end of the sheath projecting beyond the free end of said handle when attached thereto, an elongated clamping member removably connected between the inner end of the sheath and the tapered handle, said clamping member being transversely curved to neatly fit the bottom of the sheath for clamping the end of a strand of hair against said bottom, the free end of the sheath having a passage therein and a shoulder encircling said passage, said passage adapted to receive one arm of a bobby pin, the other arm being spread outwardly by the shoulder when the first arm is forced into the passage, the strand of hair after being curled around the sheath being releasable from the clamping member and shiftable beneath the outwardly spread arm of the bobby pin so that when the bobby pin is removed from the sheath with the curled strand of hair the arms of said pin will clamp the strand of hair therebetween.

2. A hair curling device comprising a sheath neatly receiving the handle of a comb, a clamping member including a transversely curved bar in engagement with the sheath for clamping the free end of a strand of hair against the sheath, a loop of spring metal extending downwardly from one end of the bar adjacent one end of the sheath, the loop having an inturned free end received between the sheath and the handle with the handle frictionally retaining the inturned end and likewise the clamping member in position on the sheath, said loop when rocked causing the curved bar to be oscillated to rock said bar away from the sheath for receiving the strand of hair between said sheath and the bar.
